No. 893,142.

PATENTED JULY 14, 1908.

C. H. BURTON.
HOT WATER RADIATOR.
APPLICATION FILED MAY 14, 1907.

UNITED STATES PATENT OFFICE.

CHARLES HERBERT BURTON, OF WASHINGTON, DISTRICT OF COLUMBIA, ASSIGNOR TO
CHARLES T. McCOY, TRUSTEE, OF WASHINGTON, DISTRICT OF COLUMBIA.

HOT-WATER RADIATOR.

No. 893,142.

Specification of Letters Patent.

Patented July 14, 1908.

Application filed May 14, 1907. Serial No. 373,567.

To all whom it may concern:

Be it known that I, CHARLES HERBERT BURTON, a citizen of the United States, residing at Washington, District of Columbia, 5 have invented certain new and useful Improvements in Hot - Water Radiators, of which the following is a specification.

This invention relates to certain new and useful improvements in hot water radiators, 10 and it has for its objects among others to provide a novel improved radiator of a portable nature designed to be electrically heated.

It comprises a radiator and a boiler in connection therewith, the boiler being inclosed 15 within a casing and within which the heating means is confined. The casing is supported upon a bracket adjacent the radiator and is preferably lined with asbestos or some suitable non-conducting material. The heating 20 plates are disposed between the casing and the boiler and the wires for supplying the current are readily connected in a well known manner. The current being turned on, the water is quickly heated and being put in circulation, any desired degree of temperature 25 may be maintained.

Other objects and advantages of the invention will hereinafter appear and the novel features thereof will be particularly pointed 30 out in the appended claims.

The invention is clearly illustrated in the accompanying drawings, which, with the numerals of reference marked thereon, form a part of this specification and in which

35 Figure 1 is a view of my improved radiator, partly in elevation and partly in section. Fig. 2 is an elevation of one of the heating plates removed, with a portion broken away and a part in section, showing the connection 40 of the wires.

Like numerals of reference indicate like parts throughout the several views.

Referring now to the details of the drawings:—1 designates a radiator of any suitable 45 material, configuration and capacity, shown as supported upon suitable feet or supports 2 and provided with a draw-off cock 3, by means of which the water may be drained from the radiator and the boiler, soon to be 50 described, when desired.

4 is an expansion tank supported on the radiator by means of the pipes 5 which afford communication between the radiator and tank. The tank is provided with a suitable

closure 6 as shown and is designed to be filled 55 with water in the usual way.

7 is a boiler having communication at top and bottom with the radiator by means of the short connecting pipes 8, as shown.

9 is a bracket supported from one of the 60 feet or legs 2 of the radiator, and adapted to support the casing which surrounds the boiler, and the heating plates which are interposed between said casing and the boiler.

10 is the casing, which is preferably provided with a non - conducting lining 11 of asbestos or analogous material. It is supported, as above stated, upon the bracket 9 and is provided with a hood 12 of metal made in sections bolted together, as at 13, for an 65 70 obvious purpose.

14 is a slab of slate or analogous material supported upon the bracket 9 within the casing and provided with a plug or connecting block 15 for communication in the usual way 75 with the wires 16 for supplying the electric current. This block supports heating plates 17 which may be made hollow as seen in Fig. 1 and preferably provided with asbestos or other non-conducting material 18. 20 are 80 the heating wires connected by the wires 21 and 22 with the source of supply, the wires 20 being arranged as shown in Fig. 2 so as to provide an extended heating surface as will be readily understood. The wires 21 and 22 85

are disposed between a recess 23 in the slate slab 14 as they extend to the connecting block, as seen in Fig. 2, and dotted lines in Fig. 1. When the heating plates are hollow 90 as seen in Fig. 1 the heating wires are disposed within the same as shown in said Fig. 1.

The operation will be apparent:—The parts being arranged as shown and the radiator, boiler and expansion tank supplied with water through the closure 6, the current is turned on and the heating plates soon become heated, and imparting their heat to the boiler the water is soon heated and is kept in circulation in the usual way.

The advantages of a radiator constructed 100 as above described will be readily appreciated, and it is evident that modifications in the detail may be resorted to without departing from the spirit of the invention or sacrificing any of its advantages.

What is claimed as new is:—

The portable hot water heating device described, comprising a radiator, an expansion

tank thereon, a bracket supported at the bottom of the radiator, a casing supported on said bracket, a boiler supported within the casing out of contact with the latter, an electric heating means within the casing and surrounding the boiler and out of contact with both the boiler and casing, and the water in said boiler and a slab of slate resting on said bracket and supporting said heating means

and having a recess receiving the wires for 10 heating said means.

In testimony whereof I affix my signature, in presence of two witnesses.

CHARLES HERBERT BURTON.
